UNITED STATES PATENT OFFICE.

FREDERICK EDWARD MILLER, OF ST. LOUIS, MISSOURI, ASSIGNOR TO ST. LOUIS CASH REGISTER COMPANY, INCORPORATED, OF ST. LOUIS, MISSOURI, A CORPORATION OF MISSOURI.

CASH-REGISTERS TAB-ACTUATING MECHANISM.

1,427,311.

Specification of Letters Patent. Patented Aug. 29, 1922.

Application filed August 2, 1920. Serial No. 400,595.

To all whom it may concern:

Be it known that I, FREDERICK EDWARD MILLER, a citizen of the United States, residing at St. Louis, Missouri, have invented 5 a certain new and useful Improvement in Cash-Registers Tab-Actuating Mechanism, of which the following is a full, clear, and exact description, such as will enable others, skilled in the art to which it appertains, to 10 make and use the same, reference being had to the accompanying drawings, forming part of this specification.

The present invention has relation to improvements in cash registers, and is more 15 particularly an improvement over Patent No. 1,080,162, to E. E. Patten, dated December 2, 1913.

The object of my invention is to provide 20 an increased capacity, i. e., to provide means for registering greater amounts than has heretofore been done in a machine of this type. The aforesaid patent is capable of 25 registering and indicating amounts only up to \$4.99 (four dollars and ninety-nine cents), while in the present improvement it is possible to register amounts as high as \$9.99 (nine dollars and ninety-nine cents), and by utilizing the same principal of 30 operation forming the subject matter of this invention, there is no limit to the amount 35 that may be registered and indicated. In order to attain this increased capacity, I have invented a new mechanism for registering and indicating "dollars" and "cents", the "five cent" and "dime" mechanism remaining unchanged.

By virtue of the present improvement, I have secured greater compactness and greater simplicity of construction, the mechanism whereby this is done being more 40 easily operated and more cheaply manufactured.

Further objects will be better apparent 45 from a detailed description of the invention in connection with the accompanying drawings, in which—

Figure 1 is a side elevation of my invention.

Figure 2 is a plan view with parts in section and other parts, having no direct bearing 50 on the present improvements, omitted.

Figure 3 is a detail view showing the lifting bail and its connection with the dollar segment, also the locking means for the handle. 55

Figure 4 is a vertical section on the line 4—4 of Figure 1.

Figure 5 is an end view of the indicator bar and associated mechanism.

Referring now to the drawings, 1 represents the frame of the machine in which a lifting bail 2 is trunnioned, and 3 is a handle pivotally mounted on a plate 4, trunnioned in the frame of the machine. A link 5 is pivoted at the rear end of the handle 3, said link being adapted to come beneath the stem 6 of any selected indicator tab as the handle 3 is swung to position over the proper notch of the front plate 7, in order to indicate the amount registered. When the handle is swung to the position shown in Figure 2, its link 5 will be free of the lifting tabs, and this latter position is the position of the handle when it is desired to indicate and register dollars only. Obviously, when the handle is in this latter position, if the mechanism whereby the dollars are indicated is not set up, it would be possible to depress the handle and consequently open the cash drawer without indicating or recording any amount, which is the case in Pat. No. 1,080,162. In order to prevent this, the handle 3 when in the position shown in Figure 2 is locked against movement by means of a depending finger 8 mounted on a rock shaft 9, said finger 8 in its normal position being immediately over the link 5 and remaining in this position until an amount is set up in the dollar actuating mechanism, when said arm is released, as 80 70 75 80 85 90 95 will more fully hereinafter appear.

Secured against the side of frame 1, is a plate 10, on which plate is mounted the mechanism for setting up or controlling the amount to be indicated by the dollar or integer tabs 11, arranged in a bank and mounted in plates 12, on one side of the machine. The controlling mechanism, to which this invention particularly relates is as follows: 100

A plate 13 is mounted on the plate 10 by means of studs 14, 14, said plate being provided with slots 15, 15, whereby it is

- slidable back and forth on the plate 10, and mounted above said plate on the end of the rock shaft 9 is a finger 16, provided with a pin 17 on its free end, said pin being held 5 in contact with an inclined edge 18, formed on the plate 13 by a spring 19. A spring 20 tends to hold the plate 13 in its home position, at which time the finger 8 is in position to lock the link 5 on the handle 3, 10 when said handle is swung to a position for indicating dollars, as shown in Figure 2. A controlling handle 21 is pivoted at 22 near the lower end of the plate 10, said handle being provided with an arcuate portion 15 23, having a number of teeth t on its edge equal to the number of dollar tabs 11. The end of the plate 13 beneath the tabs 11 is provided with a pair of spaced-apart ears 24 wherein is mounted a lifting bar 25. The 20 plate 13 is provided with a pin 26 engaging the handle 21, and upon oscillating said handle the plate 13 will be reciprocated to a position commensurate with the amount that said handle has been oscillated, and the 25 lifting bar 25 will, of course, be carried with the plate 13 and assume a position under the stem of one of the indicator tabs 11. In order that the handle 21 may be moved step by step, so as to bring the lifting bar 30 25 under any selected indicator tab, a pawl 27 is mounted adjacent the arcuate portion of the handle 21, which has its nose in the uppermost or first tooth t when the handle 21 is in its home position; said handle can 35 now be oscillated to the proper position to effect the lifting of any dollar tab, and in Figure 1 the handle is shown dotted in the proper position to raise the fifth tab from the rear, or the five dollar tab.
- 40 A second reciprocating plate 28 is positioned beneath the plate 13, said plate 28 being secured to the plate 10 by studs 29, 29 operating in slots 30, 30. The plate 28 is provided with a pin 31 near its forward 45 end, said pin resting within a slot 32 in the handle 21, and as the handle 21 is oscillated, the plate 28 will likewise be reciprocated to a position corresponding to the amount of oscillation of the handle 21.
- 50 A yoke 33 is mounted on a rod 34, said yoke having an upwardly projecting arm 35, the latter carrying a tooth segment 36 adapted to engage a gear 37, whereby the dollar wheels are rotated. The yoke 33 is 55 also provided with a downwardly projecting arm 38, the extremity of which arm 38 is provided with a pin 39, projecting through an arcuate slot 40 in the plate 10, and also traversing a slot 41 in the rear end 60 of the plate 28. It is thus seen that as the handle 21 is oscillated and the lifting bar 25 positioned beneath a selected tab 11, the locking finger 8 will be released, and the plate 28 will be reciprocated to oscillate 65 the yoke 33, so as to rock the dollar segment

36 to a position to register the amount of dollars in the counter wheel that have been set up on the indicator tab.

After the lifting bar is positioned and the dollar segment correspondingly oscillated, the handle 3 is depressed, whereby the bail 2 will be raised to effect the lifting of the designated dollar tab and restore the dollar segment to its home position, during which operation the gear 37 will be rotated and the proper number of dollars registered in the counter wheels by the actuating mechanism which is as follows:

A rocking frame 42 is pivoted on the rod 34 and is provided with an L-shaped slot 43, 70 through which a pin 44 projecting from the bail 2 extends. The rocking plate 42 is provided with an extension 45, having a pin 46 in its extremity, which pin traverses an inclined slot 47 in a lifting plate 48 slidingly 75 secured to the plate 10 by means of studs 49-49 traversing slots 50-50. The forward end of the rocking plate 42 is provided with an arcuate slot 51, having an angular extension 52, which is traversed by a pin 53, 80 projecting from a pawl 54, the nose of which pawl upon being oscillated is adapted to enter anyone of ten serrations 55 on the lower edge of the plate 13. On depressing the handle 3 and raising the bail 2, the pin 44 85 will be carried upwardly, traversing arcuate slot 56 in the plate 10, and rocking the plate 42, thereby lifting the plate 48, which latter in turn will lift the lifting bar 25 by virtue of its leg 57 engaging a pin 58 projecting from the lifting bar 25. As the plate 42 is rocked the pin 53 will be forced out of the slot 52 into the slot 51, thereby rocking the pawl 54 until its nose engages one of the serrations 55 and which will hold said pawl 90 in this position until the rocking plate 42 again returns to its home position, which it will do, upon releasing the handle 3. As the bail 2 is raised, the pin 44 thereof will engage a projection 69 on the yoke 33 and 95 force said yoke back to its normal position, during which time the segment 36 is registering dollars in the counter wheel, the gear 37 having previously been thrown in mesh with the teeth of said segment 36. The 100 mechanism whereby the gear 37 is caused to engage with the teeth of the segment 36 is the same as that set forth in the aforesaid Patent No. 1,080,162. The depressing of the pin 53 will likewise cause the pawl 27 105 to be disengaged from the teeth of the handle 21, since said pin 53 engages the rear leg of the pawl 27. Obviously, the restoring of the yoke 33 to its normal position will 110 draw on the plate 28 and likewise restore 115 said plate to its normal position, and in doing so, will likewise restore the handle 21 to its normal position by virtue of the pin 31 which engages the slot 32 of said handle. However, the plate 13 will not be restored to 120

76

100

105

110

115

120

125

130

its normal position on depressing the handle 3, said plate being locked in place by the pawl 54 and is held in its locked position throughout the entire period that the lifting bar 25 is engaged in raising one of the tabs 11. On releasing the handle 3 and allowing the bail 2 to drop to its normal position, the plate 42 will rock to its home position and on reaching the same, the pin 53 of the pawl 54 will enter the slot 52 and permit the pawl 27 to again engage the teeth of the handle 21, and the pawl 54 to again become disengaged from the serrations 55, at which time the plate 13 will be restored 15 to its normal position under the influence of the spring 20.

The plate 28 is provided with a series of teeth 59 on its upper edge above which is mounted a locking pawl 60, which pawl is held out of engagement with said teeth by means of pin 61 which bears against the lower edge of an opening in the rocking plate 42, but upon rocking the plate 42, said pawl will be depressed under the influence 25 of a spring 62, and will engage with the teeth 59 thereby locking the plate 28 against forward movement when the mechanism is set, but permitting said plate 28 to return to its normal position at the proper time. The 30 pawl 60 is provided as a safety device to prevent tampering with the mechanism or accidentally deranging the same.

A release handle 63 is slidably mounted on the handle 21 and said handle 63 is provided with an arcuate extension 64 upon which a pin 65, projecting from the pawl 27, bears. In whatever position the handle 21 may be oscillated, the arcuate portion of the handle 64 will engage with the pin 65, so 40 that, at all times, the handle 63 may be raised in order to lift the pawl 27 out of engagement with the teeth 59 of the controlling handle. The handle 63 therefore may be operated to release the pawl 27 and step 45 back the handle 21 any number of spaces, should an error be made in setting said handle 21.

It is understood that a bank of tabs may be mounted on the side of the frame opposite to the dollar tabs with actuating mechanism of its own, and said tabs may be adapted to indicate odd cents or higher multiples of dollars for instance—from 10 (ten) to 90 (ninety) dollars inclusive. In this manner, 50 the capacity of the present machine may be readily enlarged, by merely adding another bank of dollar tabs to indicate up to \$99.95 (ninety-nine dollars and ninety-five cents), or the machine may be provided with additional banks of tabs, and its capacity increased to any amount desired. It is thus seen that my invention consists of a complete registering and indicating device, and if desired, could constitute the sole registering and indicating mechanism of a cash 55

register. Obviously, it is within the purview of a skilled mechanic to modify the invention without, in any way, departing from the spirit of the same.

Having described my invention, what I claim is:

1. In a machine of the class described, a plurality of indicating tabs, lifting means adapted to be positioned beneath any one of said tabs, an operating handle adapted to 70 raise said lifting means, means for locking said handle against movement and means for releasing said locking means simultaneously with the positioning of the lifting means.

2. In a machine of the class described, an operating handle, means for locking said handle against vertical movement, a plurality of indicating tabs, a lifting bar adapted to cooperate with said tabs, means for selectively positioning said lifting bar in co-operative relation with any one of said tabs and simultaneously releasing the handle locking means, and means for restoring said lifting bar and locking means to their normal positions after the handle has been operated.

3. In a machine of the class described, a registering mechanism provided with a pinion for introducing numbers thereinto, a 95 rack segment for cooperating with said pinion, a member for positioning said segment, a controlling handle adapted to be set so as to selectively position said member, an operating handle and associated mechanism, 100 adapted to positively restore the rack segment to its normal position and to restore the controlling handle to its normal position simultaneously with the restoring of the rack segment.

4. In a machine of the class described, an operating handle, a lifting bail for cooperating with said handle, a registering mechanism having a pinion, a yoke having a rack segment adapted to rotate said pinion, a controlling handle, connecting means between said controlling handle and yoke for positioning the rack segment, and means on said bail for positively restoring the rack segment and controlling handle to their normal positions upon actuating the operating handle.

5. In a machine of the class described, a plurality of indicating tabs, registering mechanism provided with a pinion, a lifting bar for cooperating with any one of said tabs, a rack segment for cooperating with said pinion, a sliding plate for selectively positioning said lifting bar, a second sliding plate for simultaneously positioning the rack segment for counting dollars in the registering mechanism, a controlling handle for imparting movement to said plates, an operating handle for positively raising the lifting bar after the same has been positioned 130

and simultaneously positively restoring the rack segment to its normal position, thereby registering dollars, and means for thereafter releasing the sliding plate for positioning 5 the lifting bar.

6. In a machine of the class described, a plurality of indicating tabs, lifting means adapted to be positioned beneath any one of said tabs, an operating handle adapted to 10 raise said lifting means, means for locking said handle against movement, and means for automatically releasing said locking means simultaneously with the positioning of the lifting means.

15 7. In a machine of the class described, an operating handle, means for locking said handle against vertical movement, a plurality of indicating tabs, a lifting bar adapted to cooperate with said tabs, means for selectively positioning said lifting bar in 20 cooperative relation with any one of said tabs and simultaneously releasing the handle locking means, and means for automatically restoring said lifting bar and locking means 25 to their normal positions after the handle has been operated.

8. In a machine of the class described, indicating tabs, registering mechanism including a pinion, a gear segment for actuating 30 said pinion, a tab raising element, a member adapted to position said segment and element, a selective handle for setting said member, and an operating handle for positively actuating said element and segment.

35 9. In a machine of the class described, indicating tabs, registering mechanism including a pinion, a gear segment for actuating said pinion, a tab raising element, a member adapted to position said segment and ele-

ment, a selective handle for setting said 40 member, and an operating handle for actuating said element and positively returning said segment to normal position.

10. In a machine of the class described, indicating tabs, registering mechanism including 45 a pinion, a gear segment for actuating said pinion, a tab raising element, members adapted to move in straight lines to position said segment and element respectively, a selective handle for setting said members, 50 and a manually controlled operating handle for actuating said element and segment.

11. In a machine of the class described, cent tabs, dollar tabs, means adapted to be 55 positioned to actuate said cent tabs, means adapted to be positioned to actuate said dollar tabs, a machine operating handle, and means for locking said handle when neither of said tab actuating means is in functioning position.

12. In a machine of the class described, a plurality of indicating tabs, a machine operating element adapted to be selectively shifted to different positions to actuate different ones of said tabs and also adapted to 60 be shifted to a position in which it operates the machine without actuating one of said tabs, supplementary tab actuating mechanism adapted to be manually set in operative position and to be automatically operated by 65 said element, and an automatic lock for said element functioning only when neither said element nor said supplementary mechanism is in tab actuating position.

In testimony whereof I hereunto affix my 75 signature this 31st day of July, 1920.

FREDERICK EDWARD MILLER.
